(57) **CLAIM**

The ornamental design for an archery bow stabilizer, as shown and described.

DESCRIPTION

FIG. 1 is an elevated side view of an archery bow stabilizer in accordance with our design;

FIG. 2 is a front end view thereof;

FIG. 3 is a rear end view thereof;

FIG. 4 is a perspective view thereof;

FIG. 5 is a side elevational view on a reduced scale mounted to an archery bow shown in broken lines thereof; and, FIG. 6 is an exploded perspective view showing the knife that would be inserted in the cylinder of the stabilizer thereof.

The archery bow shown in phantom lines is for illustrative purposes only and is not part of the claimed design.
